UNITED STATES PATENT OFFICE.

ANGUS W. McDONALD, OF NEW CREEK DEPOT, VIRGINIA.

TANK AND CISTERNS FOR SUPPLYING LOCOMOTIVES.

Specification of Letters Patent No. 11,998, dated November 28, 1854.

To all whom it may concern:

Be it known that I, ANGUS W. McDONALD, of New Creek Depot, in the county of Hampshire, in the State of Virginia, 5 have invented a new and improved water-tank, (from which to supply locomotive engine-boilers with water,) and a new and improved cistern from which to replenish my said tank and any other in 10 common use in the United States, and a mode or plan of so connecting by pipes or hose my said tank or any other now in common use with my cistern that when such connection is formed as devised and perfected 15 by the opening of the proper valve water may be taken from my cistern (or any other constructed upon the same principle and placed in like relation to the tank) and such tank therewith replenished while it is rapidly passing such cistern, and my tank may, 20 when it is desirable so to do, be replenished from other sources than my cistern by the use of my plan or device of forming a connection (by pipes, hose &c. or their equivalents) of my tank with the water which is 25 to be taken and such water be drawn from any cistern, river, pool, or other body of it, over or under and near which such tank for the time may be, provided the level of the 30 water to be taken be not so far below the level of the tank that the pressure of the atmosphere will be insufficient to expel the air which may be in the connecting pipe or hose and force the water into the tank, it 35 having been previously rendered an exhausted receiver, to the extent it is intended to replenish it, to which invention or inventions I give the title of "The underway self-replenishing locomotive-tank and road- 40 side cistern; and I do declare that the following is a full, clear, and exact description of the construction and operation of the same, reference being had to the annexed drawing, making a part of this specification, 45 in which—

Figure 1, is a side view of cistern, tank, and pipe and hose. Fig. 2 is a top view of same, and of a double track of rail road, the cistern being located between the two tracks, 50 and at equal distance from each. Fig. 3, is a perpendicular side view of a section of the cistern, cut through the trough of it, next to the tank, along the middle of the guide way in said trough, by a plain passed parallel to

the track of the road. Fig. 4, a similar view 55 of a like section through the other trough and guide way.

The same letters upon each figure indicate or mark the corresponding parts.

A, is the cistern, made up of a pit in the center (into which the water from a natural or artificial head is to be let, in such regulated and controlled supply, as to prevent it from rising in the cistern beyond the required height) and two troughs of equal dimensions, leading each way from the pit, along and parallel to the track of the road, upon which the tank is to be transported. These troughs are separated at their top from each other, by a thin partition, in 70 which, at the bottom, there are many open spaces, to permit a free flow of water from one into the other. The object of this partition is to confine the water at the surface, within the limits of the trough, made narrower at the top by this partition. This trough, or these troughs, being filled by the water from the head, coming in through the pit, or by pipes entering the bottom of it or them. Through the center, or rather the 80 middle of each of these troughs, there is a, b, guideway along which travels and is kept in place, a wheel which sustains the trough-pipe. This guide-way commences on the outside and at each end of the trough, leading into, through and out of each trough, by an inclined way in each direction—at the same angle to the horizon, these guide ways along their whole length, and lower in the middle, than at the sides, with a uniform 85 inclination from the sides to the middle line of each. The object of which, is to incline the wheel, fixed beneath the mouth of the trough-pipe, to the middle of the guide-way. b', marks the inclined parts of this guide 90 way; c, the cistern-pit, its position and function, already described. d, the sides of the tender, which in the accompanying model and drawing, is assumed to be the carriage upon which the tank is carried, attached, of 100 course, to the locomotive.

e is a portion of the platform, which may be placed over the tank, upon the top of the sides of the tender and upon which fuel for the engine may be carried.

s is one of the open spaces in the partition, between the troughs.

f is the tank.

g is the trough pipe, *h* the tank-pipe, through which the water is passed from the trough pipe into the tank, or through hose into the tank.

5 *i* is also a similar tank-pipe, but exhibited in the drawing with a section of hose attached, instead of the trough-pipe.

10 *k* is the section of hose attached to the trough pipe. It should have *l*, a metal mouth always open to admit the water in which it may be immersed.

15 *m* is a pipe through which the water is drawn from the tank, by the engine, and pumped into the boiler.

20 I may here remark, that when the tank is carried upon a tender, and not upon the same platform or wheels that support the engine and boiler, the connection between this pipe (*m*) and the pumping apparatus of the engine, should be by an incompressible (to such an extent, at least as that a sufficient flow of water through it to supply the boiler shall not be obstructed) but flexible pipe. *n* marks the position of the two 25 valves, commanding respectively the communications between their respective tank-pipes (under each of which, one of these valves is placed) and the tank opening such communication when the arrangement is 30 made to receive water into the tank, and closing or breaking the connection when the tank is replenished; if it be intended to make it an exhausted receiver, and be so used.

35 *o* is a ball valve, provided for the escape of air and surplus water which may be forced into the tank, and closing as soon as such surplus water is pumped out of the tank.

40 I here remark, that in the model and drawing, I have filed,—the tank exhibited being a regular figure, but one such valve, situated or placed upon the highest part of the tank, is needed—but if for any purpose, 45 the tank should be made with its upper outline irregular, more than one such valve would be rendered necessary.

45 *p* is a small metal wheel fixed under the mouth of the trough-pipe, upon which said 50 pipe presses when it is let down to take in water—and the strain which it would have bear when passing through the water being in a great degree relieved by this wheel, which is fixed and intended to run upon the 55 middle of the guide-way, through and out of the trough, and will protect the trough-pipe in case the engineer shall neglect to draw it up to its proper position.

60 *q* is a cord passed over a roller fixed in the platform, one end of which, is fastened within reach of the engineer, and the other attached to the upper part of the trough pipe, near its mouth—the length of this cord should be only sufficient to permit the guide 65 wheel fastened below the mouth of the

trough-pipe, to touch and run upon the guide plain, along the bottom of the trough. By this cord, the engineer will be able, as soon as the trough-pipe emerges from the trough (having taken in water) to draw this pipe 70 into a horizontal position, under the projecting edge of the platform of the tender and then secure it till it may be necessary again to replenish the tank. When it should be let down at a point where the guide wheel 75 would strike the inclined guide-way (*b'*) out side the trough, then ascending it, to the trough and descending it, gradually immersing the mouth of the pipe.

80 *r* indicates the rails of a double-track rail road, upon which, the tank, when used on a rail road, will travel.

Having then described the several parts of my invention or inventions, and how those parts or most of them should be constructed and operated, I will proceed to show how the results aimed at, are to be obtained through my invention or inventions.

85 My cisterns should be provided along the line of the road, upon which, a tank is to be transported and from time to time replenished as the water is taken from it by the engine, which it is intended to supply,— (at uniform distances, the time or traveling time, being used to measure such distances) 90 or as nearly so, as may be expedient.) They may be built of any suitable material. The pit of the cistern should descend so far beneath the level of the earth's surface, as that the water in the lower portion of the pit, 100 may be expected not to freeze—and so high above the level of the road's surface, as to allow the water in them, and of course in the trough, which I regard as a portion of the cistern, to stand nearly, if not on a level 105 with the water in the tanks when full, and along side of the cistern.

110 The cistern should be built near the road: say, within one foot of the line of travel, and the troughs parallel to it. Their height should be such, as not to be an obstruction to the platforms of the carriage, which may travel on the road.

115 The length of the troughs (their width being restricted within certain limits, if placed between the double tracks of a rail road) will depend upon the size of the tanks to be filled, and the capacity of the connecting-pipe, through which the water is to pass from the cistern into the tanks—and the size 120 of the tank will be considered in ascertaining the number of cisterns, which should be built to accommodate a given road.

125 The tank may be of any convenient form, and carried either upon the same carriage with the boiler, or upon a tender attached to it. It should be constructed of such material and strength as will be sufficient to resist the pressure of the atmosphere, when the water is pumped out of it, and the 130

valves, (which, when open, and designed to admit water into the tanks) being closed, the said tank, becomes an exhausted receiver.

5 The tank-pipes and trough-pipes, should be of metal and sufficiently strong and rigid, to withstand the strain to which they will be subjected, when taking in water from my cistern, in passing the same at speed. The valves nicely adjusted, easily opened and closed, by means of connections with them, 10 placed within reach of the engineer, when at his proper station upon the locomotive.

The tank with its valves, thus constructed and provided with the required connecting pipes and hose—and cisterns described—established along the road intended to be traveled, may be filled for the first time, through any of the valves, such being opened for that purpose and being filled and the 15 connecting pipes brought into connection with the pumping apparatus of the engine, the fires and lighted, steam created, and the lifelike locomotive is started upon its journey. The first revolution of its wheels (if the engineer so wills it) draws a portion of the water, from the tank and forces it into the boiler, and so each successive one, till we may assume, that half the water which 20 filled the tank, has been so drawn from it, and to that extent (the valves having all been closed) the space in the tank, which this water had occupied, has become an exhausted receiver, or the tank to the extent the water has so been drawn from it, has been 25 come an exhausted receiver. At this point of time, for the purpose of illustration, we will suppose, that an accident has happened, which so long delays the engine that the water in the tank and boiler, will be insufficient to furnish a supply to the boiler, 30 till it reaches one of the established cisterns. The engine again moves on its way, intending to supply the tank from the first water within reach. It shortly arrives at a point, 35 where a stream is being crossed: the engine is halted when over the stream, and it is ascertained that the surface of the water in the stream, is about twenty feet below the level, at which the water will stand in the 40 tank when filled. To fill the tank from this stream, a section of hose (*k*) of sufficient length which has been provided for such occasions—the trough-pipe (*z*) being detached, the hose (*k*) is substituted for the 45 occasion, in its stead, the hose is unrolled, and its metal mouth, always open, descends below the surface: the valve, (*n*) is then opened, and the exhausted tank will be replenished by the operation of the atmospheric pressure upon the surface of the water in the stream. The tank being replenished, 50 the open valve is again closed, the hose drawn up, and the engine proceeds again upon its journey.

65 When near one of the established cisterns,

the engineer prepares to replenish his tank—without diminishing his speed for that purpose, he takes hold of the cord, (*q*) which having been drawn tight, has held the trough-pipe in a horizontal position, and stands ready to lower his pipe upon the inclined guide-plain, as soon as it is reached. Upon reaching it, he slackens the cord and the pipe, turning by its own weight upon the well adjusted hinge or joint around the tank pipe, the guide wheel under the mouth of the trough pipe falls upon the inclined guide plain, rolls up it and then down it into the trough, the mouth of the trough pipe, becoming gradually immersed in the water, in the trough; so soon as it is entirely immersed the engineer opens the valve (*n*) and the water rushes into the exhausted receiver at a speed exceeding probably, the rate per mile at which the tank may be traveling and such speed is lessened in proportion as the line at which the water has to pass from the trough into the tank is more tortuous and indirect. When the tank is filled, it will be indicated by the passage of the water through the ball valve, and the engineer may then close the valve (*n*) and so soon as the mouth of the trough-pipe is cleared of the water, as it mounts the inclined guide-way (*b'*) he 80 may draw his cord, (*q*) tight, and fastening it, again secure the trough-pipe in a horizontal position, and thus the tank is filled, while it is speeding on its journey. And if my cistern is used, and the tank and trough-pipe, guide wheel and cord, or their 85 mechanical equivalents, and attached to a tank of the kind now in common use, and such tank placed low enough, it may in like manner be filled in passing the cistern at speed—the water from the cistern being forced, if the progressive motion of the trough pipe through it is rapid enough into and up said pipe and through the tank pipe into the tank—and I leave it to experience to decide up the expediency of constructing my tanks, which may be made exhausted receivers, or not, at the pleasure of the engineer; or adopting a tank of any 90 commonly used form and improving it by my attachments of pipes, cord and guide wheel, or their mechanical equivalents, by the operating of which: tanks of either description in proper position, in relation to my cistern, may be replenished from my 95 cistern, when passing it under speed.

The facility of thus replenishing tanks, may render it expedient to dispense with the use of large tanks, saving thus, the carrying of unnecessary weight, or the occupation of space, which may be otherwise more profitably filled, and room be readily found upon the same carriage, upon which the engineer and boiler are carried—to place also, such reduced tank in contact perhaps 100

with the boiler or furnace, where the advantage of keeping the water in the tank at least warm, if not hot, might be attained.

What I claim as my invention and desire 5 to secure by Letters Patent is—

1. A water tan (from which to supply locomotive-steam engine boilers with water) so constructed that it may become at the will of the engineer in charge of it an exhausted 10 receiver, as the water is pumped out of it by the engine and when so exhausted, may be replenished through the pipes, hose, &c., with which I provide it, or other equivalent mechanical agents, either when at high 15 speed upon its way or when brought to a halt as hereinbefore explained.

2. An improvement upon the tank or tanks now in common use (for the supply of locomotive-steam-engine boilers with 20 water) by providing them with what I have called a tank-pipe—trough-pipe, guide wheel and (controlling) cord or other equivalent mechanical agents or aids and operated as herein before explained by which 25 such tanks may be replenished while moving at high speed from my cistern, as herein before explained.

3. A new and improved roadside cistern constructed as hereinbefore explained, or

in any other equivalent mechanical arrangement to attain the same end and located as described in relation to the tank to be replenished, from which any tank of the construction now commonly used, with my improvement (above hereinbefore claimed and 30 described) attached as well as my own tank (above described and claimed) may be replenished while passing said cistern at high speed and my own tank, if in an exhausted state, may be replenished, either when under way at any speed or brought to a halt 40 by the side of said cistern.

4. My own tank in connection or combination with my cistern as the two have been hereinbefore explained and claimed respectively and

5. My improved tank—or in other words—the tank or tanks in common use, improved as hereinbefore explained and claimed—in connection or combination with my cistern—as they have been respectively and in connection or combination with each other explained and claimed above.

February 9th, 1854.
